2,295,966

TUNING MECHANISM FOR RADIO RECEIVERS

Alexander W. Plensler, Chicago, Ill., assignor to
 Belmont Radio Corporation, Chicago, Ill., a corporation of Illinois

Application March 8, 1938, Serial No. 194,634

8 Claims. (Cl. 74—10)

This invention relates to tuning devices of the type commonly known as automatic tuning devices in which the pressing of a button automatically tunes a radio receiving set to the desired frequency corresponding to the station for which the button is marked. More particularly, the invention relates to automatic tuning devices of a mechanical nature in which the force applied to the button supplies the rotative force for turning the tuning condensers.

Quite a few automatic mechanical tuning devices have been proposed and one which has been found to be satisfactory is the type disclosed in one of applicant's prior copending applications, in which a heart-shape cam is preset by holding it in its actuated position by pressing a roller against it and rotating the tuning condensers to tune in a particular station so that the set may subsequently always be tuned to that station by pressing the roller against the heart-shape cam. In all such tuning devices there are various problems to be solved, particularly the problem of providing dependability and ease of operation with a simple and inexpensive structure. This problem was quite satisfactorily solved by my copending application mentioned. The present application is concerned with inventions which comprise further satisfactory solutions of this problem.

According to the present invention a push button which has a simple straight actuating movement similar to that of ordinary electric switch push buttons, but a little longer, is provided with an actuator having a pair of spaced laterally extending arms which engage a member mounted on a rotary shaft and having portions extending laterally from the shaft. The rotary shaft is connected to the tuning condenser and such member is moved by the arms of the actuator to a predetermined tuning position. The spaced arms of the actuator are preferably guided by a sliding coaction of the actuator with the rotary shaft so as to be dependably true in their relationship therewith. The spaced arms alone normally will not be satisfactory for rotating the shaft a full 180°, and the rotary shaft will usually be geared to the condenser shaft in approximately a 4 to 1 ratio so that a 45° movement of the first shaft, which may be called the counter-shaft, is enough to rotate the condenser shaft 180°.

The objects of the invention are for the most part apparent from the foregoing discussion, but further objects and advantages will be evident

from the following description and from the drawings, in which:

Fig. 1 is a fragmentary plan view of one form of the invention chosen for illustration.

5 Fig. 2 is a sectional view taken approximately on the line 2—2 of Fig. 1.

Fig. 3 is a similar but fragmentary view showing the parts with the actuator in released position.

10 Figs. 4 and 5 are fragmentary views corresponding to Fig. 2 but showing a modified form of the invention in extreme positions.

Figs. 6 and 7 are fragmentary views corresponding to Fig. 4 but showing another modified 15 form of the invention.

All of the forms of the invention chosen for illustration are shown in conjunction with a tuning condenser having a fixed frame 11 and a rotatable shaft 12, which must be turned through 20 180° to provide the full range of tuning. The condenser, or in reality the bank of condensers, carried by the frame 11 may be appropriately connected into a radio receiving set. In the form of the invention shown in Figs. 1 and 2 the shaft 25 12 carries a pinion 13 which meshes with a gear segment 14 by which the condenser is turned to tune the receiving set to a given frequency. The gear segment 14 is carried by a countershaft 16 to which it is keyed, the countershaft being 30 journaled by the support plates 17 and being rotated by push buttons 18 in a manner to be described.

The shaft 16 also carries a plurality of rocker arms or control members 21, one for each key 35 18. These rocker arms are normally held in fixed relationship to the shaft by friction means including washers 22 which are keyed to shaft 16 and clamped against the rockers 21 by means of spacing collars or bushings 23 and 24. The 40 clamping force may be exerted on the bushings 23 and 24 and washers 22, and hence on the rockers 21 simultaneously in any suitable manner as by letting the bushings bear against a screw 26 at one end of the shaft and screwing a thumb screw 27 on the other end of the shaft. Suitable clamping means are also more fully described in the copending applications noted above. The thumb screw 27 obviously clamps all 45 of the bushings together and against the screw 26. When the thumb screw 27 is loosened, the rockers 21 may be adjusted independently to different positions on the shaft 16 so that they may be used to tune the receiving set to different stations. Sufficient pressure is maintained to hold

the rockers temporarily in any position by a spring washer 28 and the support plates 17.

Each of the push buttons 18 is carried by an actuator 29 which includes the two legs 31, on each of which is formed a pressure arm 32 positioned to engage the arms of the rocker 21 at widely spaced points. When the key 18 is depressed, its arms 32 will shift the associated rocker 21 to the vertical position as shown in Fig. 2. If the rocker 21 were initially inclined in one direction as seen in Fig. 3, the upper arm 32 would strike it first, while if it were initially inclined in the other direction the lower arm would strike it first. Whichever arm strikes the rocker 21 first will rotate the rocker 21 until the other arm 32 strikes the rocker 21, to prevent further rotation of the rocker 21. This will of course prevent the button 18 from being pressed in further and when the finger is released from button 18, it and the actuator 29 will be returned to the original position by a return spring 33. A rubber collar or felt washer 34 may be provided on shank 29 to form a cushion between the enlarged inner end of actuator 29 and the frame 36 through which the actuator 29 slides and to which the return spring 33 is secured.

From the foregoing it will be seen that depressing a push button 18 will accurately position the corresponding rocker 21 provided that the actuator 29 is adequately guided. According to the present invention it is guided in a very accurate and simple manner by passing its legs, which are formed by its bifurcation, through a groove 38 in the bushing 23. This not only maintains the actuator 29 in proper vertical position with respect to shaft 16 but also maintains it in the proper longitudinal position along the shaft 16 with respect to the rocker 21. The button-carrying shank of actuator 29 should slide snugly in frame 36 or be biased against pivoting about shaft 16 by spring 33. In view of this accurate guiding of the actuator 29 we may be sure that if a rocker 21 is properly preset on the shaft 16, depressing the corresponding button 18 will accurately tune in the desired station.

To preset the rocker 21 on the shaft 16 for tuning in a given station, the thumb screw 27 is first loosened and the button 18 corresponding to the rocker 21 to be adjusted is depressed to bring the rocker 21 to its actuated position shown in Fig. 2. The shaft 12 is then turned manually in any suitable manner as by manipulation of a knob 39 keyed to an extension of shaft 12 to tune the receiving set to the desired station. The button 18 may then be released and, unless other rockers 21 are to be similarly preset, the thumb screw 27 may be tightened to lock all of the rockers 21 in fixed position on the shaft 16. Depressing the same button 18 will thereafter always return the same rocker 21 to its actuated position and hence tune the receiving set to the same desired station.

Although the arms 32 have been shown as simple lugs bent from the legs 31, they could be formed by antifriction rollers secured to the legs 31 if preferred.

In Figs. 4 and 5 a modified form of the invention is illustrated in which the shaft 51 carrying the rockers 52 could have an operating angle of approximately 88° instead of approximately 45° as in Figs. 1 and 2. With an operating angle of 88° the shaft 51 could be geared to the condenser shaft 12 with a ratio of slightly over 2 to 1 instead of 4 to 1. In this form of the invention the rocker 52 has been provided with

antifriction rollers 53 at each end thereof and the slide 54 is provided with a special pressure plate 56 which slopes to a point 57 at its center. In the latter half of the stroke of button 18' (Fig. 5) the action will be substantially the same as in Figs. 1 and 2. In the first half of the stroke, however, if one of the rollers 53 is turned nearly to a central position as shown in Fig. 4 the point 57 will strike said roller and thrust it away from the center position to a point where one of the extended arm portions of plate 56 may be effective to press the roller 53 until the other arm of plate 56 strikes the other roller 53.

Figs. 6 and 7 show still another modification 15 of the invention which has the advantage of independence between the button assembly and the actuating assembly. With this form of the invention the button 61 can be mounted directly 20 in the cabinet wall 62, being retained therein by a head on one end and a C-washer 63 snapped in a groove on the other end. The button 61 presses against an actuator bar 64 which may be pivoted at 66 preferably to some structure 25 which is independent of the chassis so that the chassis may be removed from the cabinet 62 separately. The actuator 64 may be drawn to its inactive position by a return spring 67 which presses the button 61 to its inactive position also. The actuator 64 has two portions on opposite 30 sides of its point of contact with button 61, which portions engage the rocker 68 which may be very similar in its mounting and its associated parts to rocker 21, although the angle of 35 rocking may be a little larger. Whenever a push button 61 is pressed, it will press the actuator 64 against one end of the rocker 68 and this end of the rocker 68 will be pressed rearwardly until parts come to rest at the position shown in Fig. 7. The use of the pivoted actuator 64 avoids all 40 danger of irregularity in automatic tuning due to loose fitting of the actuator in sliding guideways. It will be understood, of course, that in both the structure of Figs. 4 and 5 and the structure of 45 Figs. 6 and 7 there will normally be a plurality of rockers with a separate push button for each and that, as in Figs. 1 and 2, the rockers may be preset to any desired position on their respective shafts so that, when actuated, each will tune the receiving set to a different station.

From the foregoing it is seen that a plurality 50 of forms of automatic mechanical tuning apparatus have been provided, in each of which the structure is quite simple and yet thoroughly reliable and easily operated, the push button 55 in each case having a simple in-and-out movement.

The disclosures of this application are illustrative and the invention is not to be limited by them. In fact, if modifications or improvements are not at once obvious, they may be devised in the course of time to make additional use of the broad ideas taught and covered by this application. The claims are intended to point out novel features and not to limit the invention except as may be required by prior art.

I claim:

1. Automatic tuning apparatus including a shaft adapted to drive a tuning device, a rocker on the shaft extending in two directions therefrom, an actuator having spaced arm portions adapted to engage the two extending portions of the rocker and to actuate it always to the same position to turn the shaft to a position corresponding with the position of the rocker on the

shaft, means for manually operating said actuator, said actuator including at least one supporting portion extending to one side and to at least axial center of said shaft, and a bushing member on the shaft for clamping the rocker in place, said bushing member being grooved and receiving said supporting portion in guiding engagement therewith.

2. Automatic tuning apparatus including a rocker pivotally mounted about a given axis to drive a tuning device, and an actuator having laterally spaced arm portions movable generally toward points on opposite sides of said axis and adapted to contact a portion of the rocker on one side of said axis to actuate the contacted portion of the rocker generally in the direction of movement of the arm portion first contacting it, but always moving the rocker to the same position with both spaced arm portions engaging the rocker, and means for manually operating said actuator, said actuator being shaped to have its mid portion project toward the rocker and to recede outwardly therefrom in such manner that the projecting portion will initially turn the rocker to such a position that the laterally spaced arms of the actuator may readily turn it to the predetermined position.

3. Automatic tuning apparatus including a shaft adapted to drive a tuning device, a rocker on the shaft extending in two directions therefrom, an actuator having laterally spaced arm portions adapted to engage the two extending portions of the rocker and to actuate it always to the same position and turn the shaft therewith, and means for manually operating said actuator, and supporting means other than pivotal means for slidably supporting said operating means, said actuator being shaped to have its mid portion project toward the rocker and to recede outwardly therefrom in such manner that the projecting portion will initially turn the rocker to such a position that the laterally spaced arms of the actuator may readily turn it to the predetermined position.

4. Automatic tuning apparatus including a shaft adapted to drive a tuning device, a rocker on the shaft extending in two directions therefrom, an actuator having spaced arm portions adapted to engage the two extending portions of the rocker and to actuate it always to the same position to turn the shaft to a position corresponding with the position of the rocker on the shaft, means for manually operating said actuator, said actuator including a bifurcated slide straddling the shaft, and bushing means mounted on said shaft retaining said rocker in a position for engaging said spaced arm portions, said bushing means being grooved for receiving said bifurcated slide in guiding engagement therewith.

5. Tuning apparatus for a radio receiver including in combination a rotary control assembly having a rotary control member, linearly slidable actuator means for moving said control member including a projecting portion for engag-

ing said control member to initially turn the same, and having a stop portion extending to both sides of the transverse mid portion of said actuator for engaging said control member in stopping tuned position, and frame means supporting said actuator in at least two spaced apart points to slidably support the same for linear movement.

6. Tuning apparatus for a radio receiver including in combination a control member mounted for pivotal movement about a given axis, actuating means including a linearly slideable operating portion, an actuator portion having a pair of control-member-engaging-surfaces extending laterally in opposite directions from a line through the axis for said control member, and having a portion intermediate said engaging surfaces projecting toward said control member for engaging the same, with said line through the control member axis passing through the projecting portion, and frame means supporting said actuating means for linear slideable movement of the operating portion.

7. Automatic tuning apparatus including a shaft adapted to drive a tuning device, an actuator having a substantially U-shaped end portion straddling said shaft, with each leg of said U-shaped portion having an engaging portion near one end thereof, said engaging portions being opposite each other, a rocker on said shaft extending radially thereof in opposite directions, said rocker having a cam portion at each end operatively engageable with a corresponding one of said engaging portions, said engaging portions on actuation of said actuator moving into engagement with said cam portions to turn the shaft to a position corresponding with the position of the rocker on the shaft, and a bushing member for positioning said rocker axially of said shaft, said bushing being grooved for receiving said actuator legs in guiding engagement therewith.

8. Tuning apparatus for a radio receiver including in combination rotary control means having a control portion extending radially on opposite sides of the axial center thereof, an actuator for said control means having a finger-engaging portion at one end and a substantially U-shaped portion at the other end, with the legs of said U-shaped portion straddling said control means and extending to at least the axial center thereof, an engaging portion at corresponding ends of said legs extending outwardly from said legs in the same transverse direction, said engaging portions being positioned opposite each other, means on said rotary control means retaining said control portion in a position axially of said control means and in coplanar relationship with said engaging portions, and means for guiding said actuator for linear slideable movement, with one of said engaging portions on linear actuation of said actuator engaging said control portion to move said control means to a position at which said control portion is engaged by both of said engaging portions.

ALEXANDER W. PLENSLER.
